CLAIM

The ornamental design for a showerhead mount, as shown and described.

DESCRIPTION

FIG. 1 is a front isometric view of a showerhead mount. FIG. 2 is a front elevation view of the showerhead mount of FIG. 1.

FIG. 3 is a rear elevation view of the showerhead mount of FIG. 1.

FIG. 4 is a left side elevation view of the showerhead mount of FIG. 1.

FIG. 5 is a right side elevation view of the showerhead mount of FIG. 1.

FIG. 6 is a top plan view of the showerhead mount of FIG. 1; and,

FIG. 7 is a bottom plan view of the showerhead mount of FIG. 1.

The broken lines in the drawings illustrate unclaimed portions of the showerhead mount that do not form a part of the claimed design.
